United States Patent Office

Des. 225,831
Patented Jan. 9, 1973

225,831

BOTTLE

Thomas E. Brotton, 9581 Beachside Drive,
Huntington Beach, Calif. 92646

Filed Nov. 1, 1971, Ser. No. 194,790

Term of patent 7 years

Int. Cl. D9—01

U.S. Cl. D9—40

FIG. 2

FIG. 1

FIG. 3

FIG. 4

FIG. 5

FIG. 1 is a side elevational view of a bottle showing my new design;

FIG. 2 is an elevational view looking from the left of FIG. 1;

FIG. 3 is an elevational view looking from the right of FIG. 1;

FIG. 4 is a top plan view; and

FIG. 5 is a bottom plan view thereof.

I claim:

The ornamental design for a bottle, as shown.
